UNITED STATES PATENT OFFICE.

DANIEL G. BUTIS, OF NEW ORLEANS, LOUISIANA, ASSIGNEE TO IVORY GARTNER COMPANY, OF NEW ORLEANS, LOUISIANA, A CORPORATION OF LOUISIANA.

FASTENER FOR GARMENT-SUPPORTERS.

1,263,741.

Specification of Letters Patent. Patented April 23, 1918.

Application filed August 15, 1917. Serial No. 183,394.

To all whom it may concern:

Be it known that I, DANIEL G. BUTIS, a citizen of the United States, residing at New Orleans, in the parish of Orleans and State of Louisiana, have invented certain new and useful Improvements in Fasteners for Garment-Supporters; and I hereby declare the following to be a full, clear, and exact description of the same, reference being had to the accompanying drawings, forming part of this specification.

This invention relates to garment supporters, more particularly to supporters for hosiery, and is especially applicable to hose supporters designed for gentlemen's use. The primary object is to provide an exceedingly simple and efficient fastening for connecting the opposite ends of the limb encircling elastic band, when assembling the latter around the wearer.

The invention consists in certain novel details of construction and combinations and arrangements of parts, all as will be hereinafter described in the preferred form and the novel features thereof pointed out in the claims at the end of the specification.

Referring to the accompanying drawings:

Figure 1 is a perspective view of a hose supporter provided with the fastening means of the present invention.

Fig. 2 is a longitudinal sectional view taken on the line 2-2 of Fig. 1.

Fig. 3 is an enlarged detail view of the hook member of said fastening means.

Fig. 4 is a top plan view of the hook member connected to the end of the limb encircling member, and

Fig. 5 is a side elevation of the hook member connected to the end of the limb encircling member.

Like letters of reference in the several figures indicate the same parts.

The supporter of the present invention embodies the customary limb-encircling member A which is usually made of elastic webbing, one end of which is looped through a ring member B and attached to a slide C, whereby the length of the limb encircling member may be adjusted. The ring member is preferably formed broad and substantially flat for purposes which will herein-after appear. A loop of fabric is fastened in the ring member B to form arms or reaches E and E', which respectively support the two members F, F' of a clasp for

engaging the garment to be supported. This clasp for engagement with the garment to be supported may be of any preferred construction and specifically forms no part of the present invention.

At the end of member A opposite the ring member B is a hook member D. This hook member D is preferably a flat plate-like piece having a central transverse cross piece d connected with the end portions d', d² by the side portions D' D². The webbing forming the limb encircling member is passed outwardly through between the end portion d' and central cross piece d, around the end portion d² and outwardly through between the said end portion d² and central cross piece d, where the extreme end is confined by the overlying intermediate part of the webbing, thus firmly securing the hook member to the limb-encircling member, without the necessity of stitching. By attaching the hook member in this manner, the end portion d' projects backwardly from the end of the limb encircling member substantially parallel with the webbing and forms a recess d³ in which the ring member B will rest when the limb-encircling member is assembled around the limb of the wearer, as shown in Figs. 1 and 2.

As illustrated, the end portion d' is provided with a curved or arc-like contour, the radius on which said curve or arc is described being shorter than the radius of the ring member B, so that the side edge portions d', d² of the hook member constitute oppositely disposed surfaces bearing against the ring member when the two members are brought into interlocking relation at points on each side of the webbing and a sufficient distance in front of the point at which the strain on the webbing is exerted on the hook member D to overcome any tendency of the hook to cant or tilt upwardly and pull through the ring. It will also be noted that the width of the hook member D is less than the diameter of the eye formed by the ring member B, thus permitting the hook member to be readily passed through said ring member. Also, by making the ring member larger than the hook member, the latter is allowed a circular sliding movement on the flat face of the ring member so that it will always properly adjust itself relatively to the end of the limb-encircling member which is attached to the ring member.

The two members B and D of the fastening are preferably formed of sheet celluloid or other non-metallic material, the construction being such that the members may be cut 5 from the sheet of this material by means of dies and cutters, without necessitating complicated operations such as are usually necessary in the formation of metal members for the same purpose.

10. What is claimed is:

1. A hook member for garment supporter fasteners of the type wherein the ring member and coöperating hook member are attached to opposite ends of the limb encircling member of the supporter; characterized by having bearing surfaces for the ring member in front of the point at which strains on the limb encircling member are exerted on the hook member.

20. 2. A hook member for garment supporter fasteners of the type wherein the ring member and coöperating hook member are attached to opposite ends of the limb encircling member of the supporter; characterized by having bearing surfaces for the ring member on each side of the limb encircling member in front of the point at which

strains on the limb encircling member are exerted on the hook member.

3. A hook member for garment supporter 30 fasteners of the type wherein the ring member and coöperating hook member are attached to the opposite ends of the limb encircling member of the supporter; characterized by extending backwardly over one 35 end of the limb encircling member to form a recess for the reception of the ring member and by having bearing surfaces for the ring member on each side of the limb encircling member in front of the point at which 40 strains on the limb encircling member are exerted on the hook member.

4. A hook member for garment supporter fasteners of the type wherein the ring member and coöperating member are attached to 45 the opposite ends of the limb encircling member of the supporter; characterized by being substantially flat and having bearing surfaces for the ring member on its opposite sides in front of the point at which 50 strains on the limb encircling member are exerted on the hoop member.

DANIEL G. BUTTS.
